UNITED STATES PATENT OFFICE.

CHARLES H. BARNES, OF POUGHKEEPSIE, NEW YORK.

DESIGN FOR A CLOCK-CASE.

No. 37,583.

Specification for Design.

Patented Oct. 24, 1905.

Application filed August 16, 1905. Serial No. 274,483. Term of patent 7 years.

To all whom it may concern:

Be it known that I, CHARLES H. BARNES, a citizen of the United States, residing at Poughkeepsie, in the county of Dutchess and State of New York, have invented a new, original, and ornamental Design for Clock-Cases, of which the following is a specification, reference being had to the accompanying drawing, forming part thereof.

The figure of the drawing is a front elevation of a clock-case, showing my new design.

I claim—

The ornamental design for a clock-case, as shown.

CHAS. H. BARNES.

In presence of—

T. H. LEE,
C. H. OSTROM.
